UNITED STATES PATENT OFFICE.

EDWARD M. HEWLETT, OF SCHENECTADY, NEW YORK, ASSIGNOR TO GENERAL ELECTRIC COMPANY, A CORPORATION OF NEW YORK.

MACHINE FOR FORMING PORCELAIN WARE.

1,191,595.

Specification of Letters Patent. Patented July 18, 1916

Application filed March 9, 1908. Serial No. 419,925.

To all whom it may concern:

Be it known that I, EDWARD M. HEWLETT, a citizen of the United States, residing at Schenectady, county of Schenectady, State 5 of New York, have invented certain new and useful Improvements in Machines for Forming Porcelain Ware, of which the following is a specification.

The present invention relates to porcelain forming machines, and more especially to machines for drilling sinuous or non-rectilinear holes in green porcelain ware.

The object of the invention is to provide a simple and efficient device which may be operated by an unskilled laborer to drill sinuous or curvilinear holes or cavities in porcelain ware while in the unbaked or green state.

In carrying out my invention, I provide 20 a holder for the green porcelain article in which the article is definitely positioned with relation to the operative parts of the machine and also protected from accidental injuries. The holder is supported on a turret journaled in a reciprocating platen, and a drill is mounted in bearings adjacent the platen and positioned in a plane including the axis of the porcelain piece operated upon, so that upon oscillating the turret on its 25 axis, which is at right angles to the axis of the porcelain ware, the drill will bore a segmental hole therein and then withdrawing the drill and rotating the holder through 180° , again oscillating the turret, a second 30 segmental hole will be drilled meeting the first hole, the two holes so drilled thus forming a continuous sinuous hole. By reversing the holder side for side a second sinuous hole may be formed from the opposite side 35 of the porcelain ware which will interlink with the hole first formed and leave a solid 40 wall of porcelain between two holes.

For a more complete understanding of the invention, reference may be had to the 45 following detail description and to the accompanying drawings forming a part of this specification, in which—

Figure 1 is a plan of the porcelain forming machine with the article and the holder 50 shown in section; Fig. 2 is a side elevation of the same with the turret, platen and way-plate shown in section taken as indicated by line 2—2 of Fig. 1; Figs. 3, 4 and 5 are per-

spective views of the turret, platen and way-plate, respectively; Figs. 6, 7, 8, 9, 10 55 and 11 show in plan the relative positions of the holder and platen during the successive stages in forming a single segmental hole; Fig. 12 is a diagonal section of the work-holder taken on line 12—12 of Fig. 2; Fig. 60 13 is an enlarged end view of the drill in action, the material on which it is operating being in section; Fig. 14 is a similar view on a smaller scale; and Fig. 15 is a side view corresponding to Fig. 14. 65

The machine is shown mounted on a bench plate 1 which may be of cast iron of uniform thickness and secured in any desired manner to a work bench. To the bench plate 1 is attached the way-plate 2 by means of bolts 3 70 passing through lugs 4 near the corners thereof. The way-plate is in the form of an open frame having on its upper surface two parallel ways 5, a fixed stop 6 and a pivoted stop 7 intermediate the ways 5. On the 75 lower side of the plate are bearings 8 for the reception of a shaft 9 which carries an actuating lever 10 and arms 11 by which the platen may be reciprocated transversely of the machine. The platen 12 is in the form 80 of a rectangular plate with a depending peripheral flange 13 which serves to house and inclose the ways 5. On the under side of the platen are transverse projections 14 grooved to engage the ways 5. At the center of the 85 plate is a cylindrical sleeve bearing 15 extending downwardly therefrom, and concentric with said bearing is a ring projection 16 on the upper surface and a central thrust surface 17. Between the ring projection 16 90 and the central bearing surface 17 are formed two segmental apertures 18 through which the stops 6 and 7 of the way-plate project. A segmental stop projection 19 is also formed on the upper surface of the 95 platen to engage corresponding stops on the pivotal support or turret.

The turret consists of a circular disk 20 having a depending peripheral flange 21, a central pivot 22 and a concentric bearing 100 surface 23 adapted to engage the bearing surface 17 of the platen. Between the peripheral flange and the bearing surface are two stop projections 24 and 25. On the upper surface of the turret are two stop projections 26 having angle irons 27 secured to

their outer rear corners to serve as a holding means for the work-holder. A post 28 extends upwardly from the turret and carries a clamping lever 29 at its upper end which 5 bears against the work-holder and holds it pressed against the angle irons 27.

The work-holder consists of an open rectangular frame 30 of metal, preferably aluminum, and having two of its corners filled 10 and drilled at 31 to receive plungers 32 and 33 held yieldingly in place by springs 34. Attached to the rear side of the frame 30 is a sheet metal pan 35 shaped to fit the side 15 of the porcelain ware and apertured at 36 to permit the drill to pass freely therethrough. On the front side of the frame 30 is a corresponding pan 37 hinged to plunger 33 and connected by a thumb screw 38 to plunger 32 so that it may be opened to receive 20 the porcelain ware and closed thereupon to yieldingly grip it.

A bearing block 39 for the drill shaft 40 is secured to the bench plate 1 at the right of the way-plate. The shaft 40 is provided 25 with a clutch 41 for receiving the drill 42 and supporting it in the horizontal plane of the axis of the porcelain ware. The drill 42 consists of a plain shank or spindle provided at its end with a saw kerf in which is pivoted 30 a disk 43 of thin sheet steel. When the spindle rotates, this disk 43 rotates with it about its own diameter coincident with the axis of the spindle so as to serve as a routing tool, thus operating effectively to 35 remove parts of the flinty porcelain ware without disturbance of the body of the material. In Figs. 13, 14, and 15 I have indicated diagrammatically and with some exaggeration what seems to happen when a curvilinear 40 hole or cavity is being made.

Fig. 13 shows the drill 42 (greatly enlarged and with the disk 43 thicker in proportion to its diameter than would usually be the case in practice) as it would appear if 45 it could be looked at end-on through the material into which it is being forced and cutting its way,—the direction of rotation being clockwise as shown by the dotted arrow 50. Here the edge of the disk 43 is cutting alike at both sides of the axis of the spindle, owing to the fact that the disk is being continually pushed into the material. Confining the attention for the moment to the uppermost portion of the edge,—and dis- 55 regarding the fact that the disk 43 is free to rotate about its own pivotal axis in the end of the spindle,—it will be seen that the leading corner 51 of the edge is doing most of the cutting, but that (in consequence of the 60 drill's being pushed into the material) the following corner 52 is also cutting. It will further be seen that the leading corner 51 tends to wear round, somewhat as shown in dotted lines at 53, while the following corner 65 52 merely tends to become slightly obtuse

but not round, somewhat as shown in dotted lines at 54. Regarding, now, the lowermost portion of the edge of the disk 43, it will be seen that the conditions are the same; only here the leading corner is on the same side 70 of the disk as the following corner 52 above and the following corner is on the same side as the leading corner 51 above. It will be apparent, therefore, that if the disk were instantaneously turned 180° about its own axis in the end of the spindle, sharp corners would at first be presented for the main cutting and the rounded following corners would in time be worn sharp again, and that conditions would be more or less improved 75 by any turning of the disk less than 180°. It can be easily understood, then, that if the disk were thus turned often enough, or were continuously revolved fast enough, its corners would never, at any rate, become 80 very much rounded; also, that the thinner the disk the less the rounding would occur.

In Figs. 14 and 15, I have shown the disk cutting a curvilinear hole, indicating the movements of the parts by dotted arrows 85 and the principal forces to which they are subject (other than those exerted on the disk by the rotating spindle itself) by full line arrows. From Fig. 14 (which is a view similar to Fig. 13) it will be seen that the 90 resistance of the material being cut to the portions of the disk 43 at opposite sides of the spindle axis is the same,—as is shown by the arrows 55 of equal length,—so that these forces balance; it will also be seen that these forces are perpendicular to the plane of the disk, so that even if not equal they could not cause the disk to turn on its axis in the end of the spindle. From Fig. 15, which shows a mid-section through the 95 curvilinear hole, it will be seen that the disk is subject to two pairs of opposite forces 100 56, 57 and 58, 58 tending to turn it about its axis in the end of the spindle. The opposite forces shown by the arrows 56 and 57 are those due to friction of the edge of the disk with the material as the disk is pushed into the latter. Owing to the curvature of the disk's path in the material, these 105 forces will be unequal, as shown, and there will be a relative turning of the disk and the spindle. The opposite forces 58, 58 are the centrifugal forces on the halves of the disk at opposite sides of the spindle axis. Disregarding initial imperfections of the 110 drill, these forces are by themselves ineffective to turn the disk 43, not only because equal and opposite, but also, initially, because acting through the center of the disk. However, with use the disk 43 wears somewhat as indicated (with much exaggeration) by the dotted line 59 in Fig. 15, so that the centrifugal forces 58, 58 will act to one side of the center of the disk, as indicated with a great deal of exaggeration, 115 120 125 130 135 140 145 150 155 160 165 170 175 180

and any slight concurrent turning of the disk (such as under the frictional forces 56, 57) renders the centrifugal forces 58, 59 unequal, and the cumulatively increasing 5 difference between them acts in the same direction as the centrifugal forces 56, 57 to turn the disk. The turning action of these various forces is more or less supplemented or modified in consequence of the 10 periodic withdrawal of the drill 42 from the hole it has bored, of irregularities in the porcelain, and of irregularities in the drill itself, etc. It will be seen, therefore, that in the actual operation of the tool 42 any 15 point on a corner of the disk 43 is continually being automatically shifted from one side of the spindle axis to the other, so as to be first leading and then following; and in practice the edge of the disk 43 wears 20 without rounding to any extent that is material or even susceptible of detection without some very delicate method of examination, so that the tool is indefinitely self-sharpening. This is of great importance in 25 the curvilinear cutting of green porcelain and the like; for while the particles of such material are hard and flinty and are held firmly enough to abrade the metal of the disk effectively, they have not sufficient cohesion to stand the general wide-spread stress arising in an article of the material 30 from the operation of a dull tool. Under conditions of commercial manufacture, the result of using any tool that is not self-sharpening is the disruption of the articles 35 operated on; whereas with a self sharpening tool the stress is localized in a thin surface layer where the tool is actually cutting and no such trouble arises.

40 The operation of the device is substantially as follows: The holder with the porcelain piece 44 is first clamped on the turret in the position shown in Fig. 6 with the stop 24 in engagement with the projection 19 of the platen and is then rotated clockwise 45 into the position shown in Fig. 7 until stopped by the pivoted projection 7 engaging the stop 24. The operator then draws the hand lever 10 toward him so as to throw 50 the platen and the parts carried thereby into the position shown in Fig. 8 to remove the shoulder on the porcelain ware at the rear side of the drill. The forward movement of the platen carries the stop 24 to the outside 55 of and clear of the pivoted stop 7 so that the turret is free for further rotation until stop 25 engages the stationary projection 6, as shown in Fig. 9. The hand lever 10 is then thrown back carrying the platen into 60 its original position, as shown in Fig. 10, and at the same time moving the stop 25 clear of the projection 6 permitting the turret to be further rotated into the position shown in Fig. 11. The turret is then rotated to the 65 left or counter-clockwise, the stop 24 being

allowed to pass the pivoted stop 7 which is yieldingly held in place by the spring 45. The holder is then removed from the turret by the operator and turned through an angle of 180° , and the steps above described 70 are repeated to form a second segmental hole which, meeting with the first one, forms a complete aperture or sinuous hole as shown at 46 in Fig. 1. The holder is then removed from the turret turned through an angle of 90° and reversed side for side to form a second sinuous hole 47 entering from the opposite side of the porcelain piece. The porcelain piece is then removed from the holder and is ready to receive the glaze 80 as soon as the burs have been removed.

I do not wish to restrict myself to the particular form or arrangement of parts herein shown and described, since it is apparent that they may be changed and modified without departing from my invention as defined in my claims.

What I claim as new and desire to secure by Letters Patent of the United States, is:—

1. A machine for forming curvilinear 90 holes in unbaked porcelain ware comprising a rotary tool adapted to automatically change its cutting edge and be self-sharpening, a support for the ware, and means for determining the curvilinear path of the tool 95 in the ware.

2. A machine for forming curvilinear holes in unbaked porcelain ware comprising a rotary tool adapted to automatically change its cutting edge and be self-sharpening, 100 a holder for the ware, and an oscillating support for the said holder whose movement serves to determine the curvilinear path of the tool in the ware.

3. A machine for forming curvilinear 105 holes in unbaked porcelain ware comprising a rotary tool adapted to automatically change its cutting edge and be self-sharpening, a holder for the ware, and a support adapted to guide said holder relative to said tool whose movement serves to determine 110 the curvilinear path of the tool in the ware.

4. A machine for forming curvilinear holes in unbaked porcelain ware comprising a rotary tool adapted to automatically 115 change its cutting edge and be self-sharpening, a holder for the ware, and a turret for supporting said holder, said tool and turret being relatively movable to determine the curvilinear path of the tool in the ware. 120

5. A machine for forming curvilinear holes in porcelain ware comprising a rotary tool, a holder for the ware, a pivoted support for said holder, and means for shifting the pivot bearing transversely to the 125 pivotal axis and relative to said tool.

6. A machine for forming curvilinear holes in porcelain ware comprising a rotary tool, a holder for said ware, a support for said holder, and means for determining 130

intermittent rotation of said support and for shifting the axis of rotation relative to said tool.

7. A machine for forming curvilinear holes in porcelain ware comprising a rotary tool, a holder for the ware, a pivotal support for said holder mounted on transverse guides, and means whereby the extent of pivotal movement of said support is determined by its position on said guides.

8. A machine for forming porcelain ware comprising a rotary tool, a way-plate having stop projections, a platen mounted on said way-plate, and a turret pivoted in said platen and provided with stop projections adapted to engage the stops on the way-plate according to the position of said platen.

9. A self-sharpening routing tool for drilling in unbaked porcelain ware comprising a rotary spindle and a circular disk freely

journaled centrally of one end thereof on a transverse axis and adapted to automatically change its cutting edge.

10. A self-sharpening routing drill for unbaked porcelain comprising a suitable rotary spindle and a thin metal disk freely journaled thereon about a transverse axis adapted to rotate about a diameter and to automatically change its cutting edge. 30

11. A self-sharpening routing tool for curvilinear drilling in unbaked porcelain comprising a rotary spindle and a disk of thin sheet steel freely journaled at one end thereof about an axis transverse to the axis 35 of rotation of said spindle.

In witness whereof, I have hereunto set my hand this 4th day of March, 1908.

EDWARD M. HEWLETT.
